RAIL JOINT

Otto Reifurth, Immigrath Rhld, Germany

Application July 29, 1949, Serial No. 107,466
In Switzerland June 9, 1948

6 Claims. (Cl. 238—173)

1

This invention relates to an improved rail joint.

The problem of rail joints has long been known in railway technique. Attempts have continually been made to avoid or to diminish the shocks and blows produced on running over a rail joint. As is known these arise because the end of the rail sinks under the wheel pressure produced by the weight of the rolling stock resting thereon and since the wheel must rise a corresponding amount on passing over on to the end of the succeeding rail, whereupon the end of this succeeding rail must of course simultaneously be depressed a corresponding amount.

It is an object of the present invention to remove the disadvantages of known rail joints. This invention provides a rail joint which is characterised in that the two adjoining ends of the rails are connected not only by side fish plates but also by a spring assembly disposed beneath the rails, which comprises at least one pre-stressed resilient member pressed against the soles or flanges of both rails, the countersupport of said member engaging the ends of both rails.

In this way, with a suitable construction, differences in height between the adjoining ends of the rails on passage of rolling stock are prevented, so that the impacts arising on passing over the rail joints are avoided.

One embodiment of the invention will now be described by way of example with reference to the accompanying drawings, in which:

Fig. 1 shows a rail joint in side view partly in section, and

Fig. 2 shows a cross section on the line 2—2 of Fig. 1.

Referring now to Fig. 1, the end 1 of one rail rests in the usual way on a sleeper or tie 2 and the end 3 of the succeeding rail rests correspondingly on a sleeper or tie 4. The two ends 1 and 3 of the rails are joined together by the usual side fish plates 5 and fish bolts 6. In addition to this connection the rails are also joined together by a spring assembly disposed beneath them. This assembly comprises a pre-stressed compression spring 7 which rests on a countersupport and is pressed against the flanges of the two rails by a pre-stressing force of for example 15 tons. The countersupport comprises a stirrup 8 on which the spring 7 rests directly. The stirrup 8 is provided at each end with an eye 9 through which passes a bearing bolt 10. This bearing bolt is supported in the bore of carrier brackets 11 which are arranged on each side of the rail and engage with a nose or projecting

portion 12 over the foot of the ends of the rails.

When rolling stock passes over the rail joint in the direction of the arrow shown in Fig. 1, the wheel pressure first causes the end 1 of the rail to sink or flex as usual. This sinking movement is transmitted by the spring 7 and its countersupport to the end 3 of the succeeding rail. With suitable pre-stressing of the spring 7 the end 3 of the succeeding rail is depressed by the transmitted force by the same amount as the end 1 of the preceding rail, so that no, or practically no, difference in height arises between the ends of the two rails.

15 A common spring plate can be introduced between the compression spring 7 and the ends 1 and 3 of the rails.

Instead of a spring some other resilient member can be employed.

20 The spring assembly must be so constructed that it allows longitudinal displacement of the ends of the rails produced by heat expansion, which is effected in the present case either by the resilience of the vertical limbs of the stirrup 8 or else by the noses 12 sliding on the feet of the rails. Care must however be taken that the resilient member is always disposed as far as possible symmetrically with respect to the ends of the two rails.

25 The countersupport may also be of different construction, for example a one-part or multi-part housing which engages both the ends of the rails and supports the resilient member in such a way that it is pressed against the ends of the two rails with the desired pre-stressing force.

I claim:

30 1. In a rail joint, a resilient assembly to be applied to the flanges of linearly extending adjacent rail ends and between spaced adjacent ties comprising a support connected to and suspended from the flanges of the ends of the two adjacent rails, and at least one resilient member stressed between the flanges of both rails and said support, said assembly joining the two rails so that downward movement of one rail end will produce downward movement in the adjacent rail end causing both rail ends to flex downwardly upon the passage thereon of a railway wheel.

35 2. In a rail joint according to claim 1, in which a plate is provided between said resilient member and the flanges of the rails.

40 3. In a rail joint according to claim 1, in which side carrier brackets are provided for and at each end of the support, each carrier bracket having a projecting portion engaging over the side end of the flange of the rail.

4. In a rail joint according to claim 1, in which the support is in the form of a U-shaped stirrup.

5. In a rail joint according to claim 1, in which said resilient member is in the form of a helical compression spring and is pressed against the flanges of the two rails by a pre-stressed force.

6. In a rail joint, a spring assembly to be applied to the flanges of linearly extending adjacent rail ends comprising a support, at least one spring member stressed between the bottom surfaces of the two rails and said support, said support being in the form of a stirrup which is provided at each end with a bearing eye and is suspended from the flanges of the rails, a pair of carrier brackets, one each of which is arranged at each end of each bearing eye, each carrier bracket being provided on an inner side with a projecting portion engaging over an edge portion of the flanges of its respective rail end and provided with a

transverse bore, and a connecting bolt in the bores of each pair of carrier brackets and the bearing eye which latter is disposed therebetween, said assembly joining the two rails so that downward movement of one rail end will produce downward movement in the adjacent rail causing both rail ends to flex downwardly upon the passage thereon of a railway wheel.
